UNITED STATES PATENT OFFICE

2,023,499

DISPENSING DEVICE

Alfred N. Winter, Augusta, Kans., assignor to
Socony-Vacuum Oil Company, Incorporated,
New York, N. Y., a corporation of New York

Application January 22, 1935, Serial No. 2,871

2 Claims. (Cl. 214—1)

This application has to do with devices for introducing materials into other materials contained in positions more or less inaccessible. In its particular aspects, this device was developed to furnish a mechanical means of introducing poisonous dyes in powder form into gasoline contained in tank cars. Much of the gasoline now sold is dyed with chemicals of generally poisonous or irritant nature and these chemicals are frequently added to the gasoline in the tank car just before shipment. Normally the dyes used are in powder form and it has been necessary for the loader to reach down into the dome of the tank car as far as possible and dump the dye powder from a paper sack, can, or other container. The vapors rising from the gasoline carry the powdered dyes out of the car and into contact with exposed portions of the skin of the loader. Serious skin diseases and poisoning frequently result from this contact of the powder with the skin.

It is an object of this invention to devise a means whereby a dye or other ingredient can be conveniently introduced into another material contained in a relatively inaccessible place.

In order that this invention may be understood, reference is hereby made to the drawing which is attached to and made a part of this specification. The single figure of this drawing shows in perspective the device of the invention. This device consists of a hollow tube 1 of suitable length; to one extremity is affixed a handle 2. The other end of the tube 1 is slit and flattened out to form a tongue or lip 3 to which is attached a bar of flat iron of say one inch in width, designated by numeral 4. Running through the interior of tube 1 is a rod 5 to which is attached a handle 6. Upon member 4 there are placed two small headed pegs or rivets designated as 7. Attached to the lower end of rod 5 is a trigger member 8, having slot 9 through which these pegs 7 project in such manner that the trigger member 8 actuated by rod 5 and handle 6 can be reciprocated with respect to tube 1 and member 4. A container carriage member 10 is secured to the extremity of member 4 by means of a hinge 11. This member 10 carries two springs 12 of proper shape and size to hold a container for the material to be dispensed, this container being designated by the numeral 13. The upper end of member 10 is fastened so that it may be placed under and retained by the end of trigger member 8 when member 8 is in extended position. The container 13

is provided with a cover 14, and the trigger member 8 is extended in U form so that one end of it having thereon a small catch 15 serves to engage the ring 16 on cover 14 and remove the cover of the can at the same time that the other end of the trigger member 8 releases the can carrier. A spring 17 is attached to member 4 and so compressed between members 4 and 10 when 10 is in the locked position that upon release of 10 by trigger member 8 the can carrier 10 will 10 be thrown forcibly into an extended position causing discharge of the contents therefrom. To assure complete discharge of the contents of the can a resilient spring stop member 18 is provided against which the moving can carrier bar 10 will 15 contact, bringing the can to a stop with a snapping motion, serving to thoroughly remove the powdered contents of the can.

I claim:

1. In a dispensing device, an elongated body 20 member, a handle affixed thereto, upon the opposite end of the body member a carriage member, affixed to the extremity of the body by a hinged joint and adapted to be carried in a refolded position against said body member, a retractable 25 stop to retain said carriage member against said body member, control means whereby said retractable stop may be operated, a spring normally compressed between said body and said carriage when in refolded position, acting to throw 30 said carriage outward upon release, and container holding means attached to said carriage member.

2. A dispensing device comprising an elongated body member, a handle affixed thereto, upon the opposite end of the body member a carriage member, 35 affixed to the extremity of the body by a hinged joint and adapted to be normally retained in a refolded position against said body member, a retractable stop member mounted upon said body member adjacent the inner end of the refolded carriage member and acting in its extended position to retain said carriage in the refolded position, control means whereby said stop member may be operated, a spring normally compressed between said body and said refolded carriage member, adapted to throw said carriage outward upon release, container holding means attached to said carriage member, and a resilient stop attached to the body member adjacent the hinge and positioned to limit the travel of the 45 carriage when thrown outward.

ALFRED N. WINTER.
